UNITED STATES PATENT OFFICE.

JOHN J. MCINTIRE, OF OAKLAND, CALIFORNIA.

EGG AND FRUIT CARRIER.

SPECIFICATION forming part of Letters Patent No. 251,617, dated December 27, 1881.

Application filed October 18, 1881. (No model.)

To all whom it may concern:

Be it known that I, JOHN J. MCINTIRE, of 5
Oakland, county of Alameda, State of California, have invented an Improved Egg and Fruit
Carrier; and I do hereby declare the following
is a full, clear, and exact description thereof.

My invention relates to certain improvements
in cases for transporting eggs, fruit, or other
similar articles; and it consists in a novel meth- 10
od of cutting, uniting, and locking the strips
which form the compartments that contain and
separate the eggs, and that are placed in tiers
one above the other in suitable cases, each
tier having a loose bottom or diaphragm inter- 15
posed between it and the next set of compart-
ments.

Many forms of compartment-cases have been
constructed, most of which have one or both of
the sets of transverse strips notched upon the
edges, and as these strips are usually made of
pasteboard, for economy, these cut edges are
easily folded down or destroyed by handling
and the breaking of eggs, so as to soon render
them useless.

25 My invention contemplates the use of two
sets of strips, those running in one direction hav-
ing slots extending transversely across the cen-
ter, but not extending to the edges. The other
set of strips are sufficiently wide to just pass
30 through and fill these slots, and they have small
central slots just where they meet the other
set of strips, through which a narrow strip of
material passes alternately to one side and the
other of the first-mentioned strips, so as to form
35 a lock.

Referring to the accompanying drawings for
a more complete explanation of my invention,
Figure 1 is a perspective view of my invention.
Fig. 2 is a top view, showing the position of
40 the locking-strips. Figs. 3 and 4 are views of
the separated strips.

A A are a series of strips, which may be
made of thin veneers of wood, of metal, or of
pasteboard or other suitable material. These
45 strips are made of the width required for the
depth of the compartments. Each strip has
slots B made at intervals to receive other strips,
C, which pass through them transversely to
form the compartments. The slots B are made

across the strips A, but do not extend to the 50
edges, which are thus left unbroken, and the
strips are much stronger than if cut or notched
at the edges. The strips A are made exactly
alike from end to end. The strips C are of a
width which just permits their passing through 55
the slots B. Each strip C has short slots or
holes D made through it at the points where
the strips A and C cross when in place. These
slots or holes D are intended to receive the lock-
ing-strips E, which are made of a size and shape 60
to fit the holes, so that between the first two of
the strips C they will lie upon one side of the
strips A. Then they pass through the holes
or slots D and extend between the next two
of the strips C upon the opposite side of the 65
strips A, and so on through the set of com-
partments, passing alternately from one side
to the other of the strips A at their points of
junction with the strips C, in the manner of
weaving, as shown in Fig. 2. This forms a per- 70
fect lock, holding the parts firmly in place and
allowing the sets of compartments to be folded
up for transportation when taken out of the
case.

All of the strips A are made precisely alike 75
from end to end, and all of strips C are also
alike from end to end, so that any of them will
fit together to form a set of compartments; and,
if desired, they might be cut or punched with
their slots from long strips and afterward cut 80
off to the proper lengths, as there is no neces-
sity to form the ends of the strips in a different
manner from the central portion to form a lock.
The spaces above the edges of the strips C give
a perfect ventilation around the contained eggs 85
or other articles, while at the same time the cen-
ter, where the eggs most nearly approach each
other, is protected by the thickness of the ma-
terial of which the strips are formed. The
edges, not being in any way cut or notched, will 90
not be easily broken down if the material be-
comes dampened in any manner.

The compartment-strips are easily made,
and may be rapidly put together, and the lock 95
is simple and efficient.

Having thus described my invention, what I
claim as new, and desire to secure by Letters
Patent, is—

1. In combination with the strips A, having slits to receive the cross-strips C, the narrow locking-strips adapted to pass through the perforations of both the strips A and C and hold 5 such strips in place.

2. In combination, the strip A, having slits extending for nearly its width, the strip C, with narrow slits at substantially the point where it intersects with the strips A, and the locking-

strip D, passed through both strips at their 10 intersection and extending alternately on opposite sides of the strip A.

In witness whereof I hereunto set my hand.

JOHN J. McINTIRE.
